LATERAL DRILL FOR WELLS

James D. Hall, Jr., Cleburne, Tex.

Application November 2, 1940, Serial No. 364,079

16 Claims. (Cl. 257—1.6)

This invention relates generally to the class of well drilling and pertains particularly to improvements in devices for forming lateral bores in the earth from the lower part of a well hole.

In well drilling operations it frequently occurs that the oil production of the well is seriously retarded as a result of particular earth formations surrounding the well hole. Under these circumstances it is necessary to break out the earth from around the well hole and this is done in a number of different ways such as by the use of dynamite or other explosive.

The present invention has for its primary object to provide an improved form of lateral drill mechanism by means of which any number of bores or passages may be formed in the earth radially of the well hole at desired elevations so that the oil in the surrounding formation may again flow freely into the well hole to be removed according to the usual methods.

Another object of the invention is to provide a lateral drill mechanism in which a drill head may be extended longitudinally through the well hole and caused to turn at a 90° angle thereto and rigidly held while it is rotated to cut into the earth, the holding means for the drill being such that the drill can be turned and made to enter the earth without the possibility of it shifting out of starting position.

Still another object is to provide a lateral drill mechanism in which the drill stem is of a flexible character so that it may be rotated while it is bent in a curve and in which there is provided a flexible extensible and retractable guide through which the flexible drill stem passes to the wall of the well hole so that such stem may be rotated without buckling or breaking.

Still another object is to provide a lateral drill mechanism in which a flexible drill stem guide and a flexible drill head carrying stem are assembled in a novel manner in a rigid guide casing so that they may be conveniently introduced into a well hole while in parallel or coaxial relation and then extended from the casing laterally into the well hole so that the drill may be caused to enter the wall of the well hole at a desired elevation.

Still another object is to provide in a lateral drill mechanism of the above described character, a construction wherein a reverse circulation may be employed for removing from the well hole the cuttings of the formation into which the drill head penetrates.

The invention will be best understood from a consideration of the following detailed descrip-

tion taken in connection with the accompanying drawings forming part of this specification, with the understanding, however, that the invention is not to be confined to any strict conformity with the showing of the drawings but may be changed or modified so long as such changes or modifications mark no material departure from the salient features of the invention as expressed in the appended claims.

In the drawings—

Fig. 1 is a view in longitudinal section on the lower part of a well hole showing partially in side elevation and partially in section the drill mechanism of the present invention.

Fig. 2 is a view partially in longitudinal section and partially in side elevation of the flexible drill stem and a portion of the rigid drill stem with which it is connected, together with a sectional view of the drill head.

Fig. 3 is a longitudinal sectional view through a portion of a group of the hinged coupled rings making up a part of the drill stem structure.

Fig. 4 is a sectional view on the line 4—4 of Fig. 2.

Fig. 5 is a longitudinal section through the lower portion of the guide casing showing the extended flexible bit guide and a portion of the extended flexible drill stem in side elevation.

Fig. 6 is a detailed longitudinal section through a portion of the guide casing showing details of construction relating to the guide roller and associated parts.

Fig. 7 is a view in elevation of one side of the flexible bit guide showing the latching means between the sections thereof.

Fig. 8 is a sectional view on the line 8—8 of Fig. 7.

Fig. 9 is a sectional view on the line 9—9 of Fig. 6.

Referring now more particularly to the drawings, the numeral 1 designates the earth wall of a well hole into which hole is shown extended the casing 2. Through this casing the drill mechanism embodying the present invention is lowered into the lower end of the well hole so that the drill of the mechanism may enter the earth wall below the casing, as illustrated in Fig. 1. This drill mechanism is made up of three primary units, which comprise the rigid guide casing indicated as a whole by the numeral 3, the partially flexible and partially rigid bit stem guide or bit guide, which is indicated generally by the numeral 4 and the flexible drill stem upon one end of which the drill head is carried. indi-

cated as a whole by the numeral 5. This flexible stem is connected at its other end with the drill pipe or rigid drill stem, which is indicated by the numeral 6.

The guide housing 3 comprises the relatively long cylindrical body 7 which is lowered into the well hole to assume a vertical position therein, as shown in Fig. 1, and the lower end of this body has adjustably secured thereto the supporting foot 8 by means of which the position of the body and of the drilling mechanism as a whole may be set, so as to cause the drill or bit to enter the earth wall at a desired elevation.

The wall of the tubular body is provided at a desired location above the lower end of the body with the opening 9 and there extends from the lower edge of this opening upwardly into the body to merge with the wall of the body upon the side thereof opposite from the opening, the curved floor 10, see Figs. 5 and 6, which functions as a guide means for the flexible bit guide when the same is lowered through the guide casing, causing the bit guide to turn outwardly through an arc of approximately 90° so that the drill may enter the earth wall on a line 25 perpendicular to the axis of the well hole.

Adjacent the lower end of the floor 10, an opening 11 is formed, see Fig. 6, in which is secured the open top of a box 12 which houses a coil spring 13 and a follower 14, which rests upon the spring and which is pressed outwardly by the spring until its outer end comes flush with the surface of the floor.

Formed longitudinally of the floor 10 from the lower side of the box 12 are the spaced guides 15, Fig. 9, the open top of the box being located between these guides and extending the full width of the area between them. These guides 15 maintain in position across the space between them a roller 16 which includes the two circular or roller bodies 17 which are connected together by a central bar 18 and the axially extending trunnions 19, the ends of which are loosely engaged in the guides 15, as shown in Fig. 9. These guides 15 for the roller 16 extend from the box 12 to substantially the upper end of the curved portion of the floor 10, and from this point on through the length of the guide casing there are formed the spaced parallel ribs 20, Fig. 8, which provide a guide groove 21 for the purpose 50 hereinafter described.

At the top of the opening 9 there are mounted upon the inner side of the wall of the guide casing the two rollers 22, Figs. 6 and 8. These rollers are supported upon substantially parallel axes which extend transversely of the casing and the peripheries of the rollers are spaced apart, as shown in Figs. 7 and 8. As is also shown in Fig. 8, these rollers are directly opposite from the ribs 20, so that the space between the rollers substantially is diametrically opposite the guide groove 21.

The flexible guide 4 for the drill stem 5 is made up of a plurality of short cylindrical segments or sections 23, the ends of which are cut at a slight oblique angle to the axis so that when such sections are in alined relation as shown in the upper part of Fig. 5, they will be in contacting relation upon one side of the tubular body which they combine to form and through the major part of their opposed edges, they will be in spaced relation as indicated at 24. At the back of each of the sections 23, there is formed a rib 25 which extends at its ends beyond the ends of the section. These extended ends of the ribs are pivot-

ally joined together as indicated at 26, so that the several sections making up the flexible portion of the bit guide are hingedly joined together and these hinge ribs 25 are located in and slide in the guide groove 21. The lower or last one of the hinge ribs 25 in the series, here indicated by the numeral 25', Fig. 5, terminates in a hook 26 which is adapted to engage with the bar 18 forming a part of the roller 16. This engagement of the hook 26 with the roller 16 occurs when the flexible guide is drawn into the casing, at which time the roller 16 will be pressed by the hinge ribs into the receiving box 12 which is provided for it at the lower ends of the guides 15. As shown in Fig. 5, when the roller is pressed into this box, it will force the follower 14 inwardly against the spring 13 and thus the roller will be partially removed from the path of the hingedly connected ribs of the portions 23 of the bit guide and allow the bit guide to move inwardly or outwardly with respect to the casing. As the bit guide moves in, the hook 26 will take hold of the bar 18 of the roller and as the bar moves into the space behind the bill of the hook, the roller will move out of the box 12 and will ride up along the floor 10 to the upper end thereof.

At opposite sides of the portions 23 of the bit guide, each portion has a pair of ears 27 formed which extend above its top edge and which receive between them the adjacent edge of the next portion. These ears serve to maintain the portions in the proper alinement particularly after the edges thereof have been brought into abutting relation when the guide is bent into the curve shown in Fig. 5, as it passes downwardly along the curved floor 10.

The formation of the guide into the curve or bend shown in Fig. 5 and its maintenance in this condition is accomplished by means of a series of latches which are carried upon the sides of the portions 23 of the bit guide opposite from the hinge ribs 25. As shown in Fig. 7 each of these portions 23 carries a pair of latches, one latch of the pair being indicated by the numeral 28 and the other by the numeral 29. As shown, each of the latches is pivotally supported upon a pivot pin 30 and the latch 28 is provided with a bill 31 and two longitudinally spaced notches 32 and 33, all of which are at one side of the pivot pin on which the latch rocks. The opposite end portion of the latch 28 is extended to form the tail piece 34. The other latch 29 of each pair has a bill 35 adjacent its pivot and a notch 36 adjacent the end thereof which is nearest the pivot for the coacting latch 28 and which is also nearest to the bill 31 of the coacting latch 28. Upon the opposite side of the pivot 30 for the latch 29, this latch is formed to provide a straight tail piece 37. As is shown in Fig. 7, the pivots 30 for the pair of latches upon each section 23 are spaced longitudinally of the section and they are offset only slightly from a line running longitudinally of the section. Also each of the latches has its tail portion at a slight angle with respect to the other end portion and thus it will be seen that when the tail portions are in parallel relation as the upper pair of latches of Fig. 7 is shown, the latches will be out of coupled relation.

Each of the flexible guide sections 23 carries a latching pin 38 which is adjacent the lower edge of the section and disposed at the inner side of the tail piece 37 of the latch 29. This latching pin is engaged in the notch 32 of a latch 28 when the latter has been oscillated in the man-

ner hereinafter described by a roller 22 as the latch passes the roller.

As is shown in Fig. 7, each portion 23 of the flexible guide has the latch 28 thereon disposed entirely or fully between the ends of the portion while the adjacent latch 28 has one half of its body overlying the adjacent side of the portion 23 to which it is attached while the other half of this latch extends beyond the adjacent end of the supporting portion and across the end of the next following portion. This extended notched part or head of the latch 28 moves toward the latching pin 38 of the following or trailing portion 23 when the latches pass between the closing rollers 22, so as to hook the pin 38 into the notch 32. The roller 22 oscillates the latch 28 as the roller passes over the head portion of this latch, so as to swing the head into parallel relation with the guide and the head portion of the associate latch 28 is likewise swung into parallel relation with the axis of the guide when it passes across the adjacent roller 22. From this, it will be readily seen that as each pair of latches moves between the latch closing rollers 22, the heads of the latches will be swung into parallel relation so that the bill 31 of each latch 28 will be oscillated into the receiving notch 36 of the adjacent latch 28 and the bill 35 of each latch 28 will be oscillated into the receiving notch 33 of the adjacent latch 28. At the same time each of the latching pins 38 will be engaged in a notch 32 of the preceding latch 28. This closing and interlocking of the latches occurs also as the portions 23 of the guide advance onto the curve of the upper part of the floor 18 so that the gap between the adjacent ends of the portions 23 is closed and the latches simultaneously hooked together, in which position they remain to hold the portions in the curved relation in which they are shown in the lower part of Fig. 5. When the latches are thus coupled together, it will be seen that the tail portions 34 and 37 thereof will be directed outwardly or obliquely to the axial center of the guide and thus it will be understood that as the guide is drawn back or retracted into the casing 3, the latches will be disconnected one from another as they pass between the rollers 22 since the rollers will force the tail portions of the latches inwardly into parallel relation and will swing the heads of the latches outwardly.

The supporting pins 30 for the pair of latches upon each guide portion 23 secure in place over the latches a cover or cap plate 39, which is shown in section in Fig. 8, and in edge elevation in Figs. 1 and 5. Of course, the rollers 22 are sufficiently thin to bear against the latches between the plates 39 and the sections 23 carrying the latches so that they will function smoothly to oscillate the latches to engaged and disengaged position as described.

The upper portion of the guide 4 comprises a straight pipe section 40, Fig. 1, to the lower end of which the segments or portions 23 are connected. This pipe portion of the guide moves down into the upper end of the guide casing 3, as shown in Fig. 1, and for a portion of its length starting at the upper end, this pipe section is increased in diameter, as indicated at 41, to receive the couplings on the drill stem 6. Also this enlarged portion 41 of the pipe 40 limits the downward movement of the flexible bit guide into the casing 3 by contact with the upper end of the casing or with the collar 42 which is fitted in the upper end of the casing and snugly encircles

the pipe 40, as shown in Fig. 1. The total length of this guide depends entirely on the amount of weight desired to force the guide to follow the bit successfully, therefore, it will be readily understood that the length of the pipe 40 and of the section of the guide made up of the segments 23 may vary in different devices.

Since it is necessary that the bit used in connection with this mechanism be of exact size to permit the guide to follow it into the new hole where it begins its turning operation and also to allow it to be drawn up inside of the guide case, it is necessary to employ a means for holding the guide in a straight position and steady so that there will be no side play, and since there is not sufficient room between the bit when it is in the guide case and the floor of the guide case for a fixed groove such as is indicated by the numeral 21 in Fig. 8, use is made of the spaced guides 15 and the guide roller 16, which is held by such guides in working position.

The flexible drill stem 5 is illustrated in detail in Figs. 2, 3 and 4. This flexible stem, which is coupled with the lower end of the drill stem or pipe 6, is made up of a series of rings 43, the edges of which are defined by a number of wide square teeth 44 which intermesh with the teeth of the other rings. The inner surfaces of the teeth of the rings are provided with the circumferentially extending grooves 45, Figs. 2 and 3, and when the ring teeth are in intermeshed or interconnected relation, these grooves align to form complete circles in which are placed the resilient coupling rings 46 which lock the rings 43 together but permit them to have a degree of relative movement so that they form a flexible tube. The uppermost one of the rings 43 is of special form and is indicated by the numeral 43' and this upper ring is interiorly enlarged and screw threaded, as indicated at 47, to threadably receive the lower end of the stem 6. Also at the inner end of the enlarged portion 47 of the ring 43', there is formed a shoulder 48 for the purpose hereinafter stated. The lowermost one of the flexible guide rings 43 is also of special form, as is indicated by the numeral 43'', this ring being exteriorly threaded, as indicated at 49. The ring 43' is threaded into the hollow drill head 50 which has water passing apertures 51 leading through the tip thereof.

The rings 43, 43' and 43'' have axially extending passages 51 therethrough and through these passages extend steel cables 52 which thread the rings together. The teeth in these rings 43, 43' and 43'' are offset slightly from one another so that they do not run in a parallel line lengthwise of the flexible stem but are slightly staggered around the stem so that the cables make a complete turn around the tubular portion or core of the stem about every five or six feet. This keeps the tension the same on all of the cables while the device is in operation. Sufficient play in the cables is allowed for to make one bend only.

Lining the interior of the rings and of the tubular body which they combine to form is an oil-proof rubber tube or hose 53. The upper end of this hose is turned outwardly over the shoulder 48 and is pressed against the shoulder by the lower end of the stem 6 which, as shown, bears against a washer 54 which is inserted between the end of the stem and the upper end of the rubber tube. The lower end of the ring 43'' is also shouldered as indicated at 55, and the lower end of the tube 53 is turned out against

this shoulder and is pressed thereagainst by the portion 56 of the drill which bears against a washer 57 interposed between this portion of the drill and the end of the ring 43".

Lining the rubber hose and preventing the same from collapse inside of the tube formed by the coupled toothed rings, is a coiled metal lining strip 58 which forms a complete metal tube inside of the hose. The upper and lower ends of this metal tube are flanged, as indicated at 59 in Fig. 2, and these flanges are forced against the out-turned ends of the rubber tube so that they also take part in pressing the ends of the rubber tube against the shoulders of the enclosing rings thereby forming a seal at the ends of the rubber tubing which prevents the fluid which surrounds the outside of the flexible drill stem under pressure from entering the stem at these places.

In the operation of the present lateral drill mechanism, any suitable above-ground equipment is used, such as is commonly employed in "drill in" and "clean-out" work for establishing a reverse circulation system through the well hole and through the drill mechanism. By this system the circulating fluid is forced down into the well around the drill stem to the bit where it picks up the cuttings made by the bit and carries them out through the drill stem by way of the bit openings 51 and the passage through 30 the flexible portion 5 and the drill stem pipe 6.

From the foregoing, it will be readily apparent that the mechanism herein described provides a strong, durable and reliable means for forming lateral drill holes in the earth wall at the lower end of a well hole and that such mechanism is designed to function smoothly and without the possibility of trouble developing which might necessitate leaving any part of the equipment in the well hole.

What is claimed is:

1. A drilling mechanism for wells, comprising a tubular casing adapted to be disposed vertically in the lower end of a well hole and having a side opening, a drill stem coaxial with and adapted to extend into the casing, a flexible tubular extension upon the lower end of said stem, a bit upon the end of said extension and having water openings communicating with the interior of the extension, and a segmented tubular guide movable through the casing and through said opening to extend laterally therefrom to a working position and having said tubular extension therein and extensible from the lower end thereof after the guide has stopped in said working position for the penetration of the bit into the wall of the hole.

2. A drilling mechanism for wells, comprising a tubular casing adapted to be disposed vertically in the lower end of a well hole and having a side opening, a drill stem coaxial with and extensible into the casing, a flexible tubular extension upon the lower end of the drill stem, an apertured drill head upon the lower end of the flexible extension and opening thereinto, a guide for and enclosing said flexible extension, said flexible extension being axially shiftable and extensible from the end of the guide, said guide being housed within the casing and being extensible therefrom through said wall opening, and means for effecting the curving of said guide into a fixed arc toward the wall of the drill hole as the guide is extended through the casing wall opening whereby to direct said flexible extension and bit directly into the hole wall.

3. A lateral drilling mechanism for wells, comprising a tubular casing adapted to be disposed vertically in the lower end of a well hole and having a side wall opening, a tubular guide within the casing and including a lower end portion of flexible construction for extension laterally from the casing through said wall opening into a fixed working position, means for bending said tubular portion of the guide in an arc as it is extended from the casing through said opening, means for holding said tubular portion rigid after it has been bent into and throughout the full extent of said arc, a flexible tubular bit stem slidable through and extensible from the lower end of said guide, after the same is fixed, a bit upon the lower end of said bit stem, and a drill stem extending into the guide and connected with the bit stem, said bit having apertures leading into the bit stem and said bit stem being retractible into the casing with the guide.

4. A lateral drilling mechanism for wells, comprising a tubular casing adapted to be disposed vertically in the lower end of a well and having a side opening, a flexible tubular guide within the casing and extensible through said side opening, a flexible tubular bit stem extending through and slidable within and extensible from the lower end of said guide, a drill head upon the lower end of the stem having water apertures opening into the stem, the other end of said bit stem being coupled with a drill stem, said guide and bit stem being movable into and out of the casing through said opening, said guide being made up for a portion of its length from the lower end thereof of a plurality of pivotally joined segments, means for turning the segmented portion of the guide in a desired direction as such portion is extended through said opening, and means upon the outer sides of the segments for securing the segments together against relative movement as the segmented portion is extended from the casing in the desired direction and for releasing each segment as it moves back into the casing.

5. A lateral drill mechanism for wells, comprising a tubular casing adapted to be disposed vertically in the lower end of a well hole and having a wall opening, a downwardly and laterally curving floor in the casing leading to the lower edge of said opening, a tubular guide slidable through the casing and having a lower portion made up of a plurality of connected relatively movable segments, said floor functioning to turn the segmented portion of the guide laterally as it passes through the opening, a plurality of latch members carried by and upon the outer sides of the segments for interconnection one with the other as the segmented portion is turned laterally in passing through the opening, means adjacent the opening for engaging and shifting the latch members to effect coupling of said latches together as said portion passes through the opening, a tubular flexible drill stem slidable through the tubular guide, and a drill head carried upon the lower end of said drill stem.

6. A lateral drill mechanism for wells, comprising a tubular casing adapted to be disposed vertically in the lower end of a well hole and having a wall opening, an articulated tubular guide within the casing and extensible therefrom through said opening, means for effecting the turning of the guide along an arcuate path as it passes through said opening, coacting means between the casing and the guide for making said guide rigid as it passes through said opening whereby it will maintain its curved form, a flex-

ible tubular bit stem extending through and slideable in the guide and projecting at its lower end beyond the lower end of the guide, and a bit carried upon the lower end of the flexible stem, the bit stem and bit being axially shiftable through and from the lower end of the guide, the upper end of the flexible stem being adapted for connection with a drill stem.

7. A lateral drilling mechanism for wells, comprising a tubular casing adapted to be disposed vertically in the lower end of a well hole and having a side wall opening, a tubular guide extending into said casing and comprising a relatively long one-piece upper portion and a segmented lower portion, the segments of the lower portion being pivotally joined together, the pivotal connections between the segments including ribs extending axially of the segments and aligned to form a single guide rib extending longitudinally of the tubular guide, a guide groove within the casing in which said rib slides, said groove leading to the lower part of the opening, latching members carried by the segments upon the sides thereof opposite from said rib, said latching members being relatively movable for interconnection with one another only when the segments have been relatively oscillated to form the tubular guide in an arc, means for effecting the formation of the tubular guide in an arc as it is extended through the opening, means adjacent said opening for interconnecting said latching members as the guide is formed in the arc, a tubular bit stem extending through the guide, a bit head carried upon the lower end of the stem, and the upper end of said stem being formed for connection with a drill stem.

8. A lateral drilling mechanism for wells, comprising a tubular casing adapted to be disposed vertically in the lower end of a well hole and having a side wall opening, a tubular guide extending into said casing and comprising a relatively long one-piece upper portion and a segmented lower portion, the segments of the lower portion being pivotally joined together, the pivotal connections between the segments including ribs extending axially of the segments and aligned to form a single guide rib extending longitudinally of the tubular guide, a guide groove within the casing in which said rib slides, said groove leading to the lower part of the opening, latching members carried by the segments upon the sides thereof opposite from said rib, said latching members being relatively movable for interconnection with one another only when the segments have been relatively oscillated to form the tubular guide in an arc, means for effecting the formation of the tubular guide in an arc as it is extended through the opening, means adjacent said opening for interconnecting said latching members as the guide is formed in the arc, a tubular bit stem extending through the guide, a bit head carried upon the lower end of the stem, the upper end of said stem being formed for connection with a drill stem, said bit being retractible with the guide and with the bit stem through said casing opening into the casing, a roller support for the guide disposed beneath the said rib within the casing adjacent the lower part of said opening, said roller support being movable with the guide along a path extending substantially longitudinally of the casing, and means at the lower end of said rib for effecting a detachable connection with the roller support as the guide and bit are drawn into the casing for the move-

ment of the roller therewith longitudinally within the casing.

9. A lateral drilling mechanism for wells, comprising an elongated tubular casing adapted to be disposed vertically in the lower end of a well hole and having a side wall opening, a downwardly extending curved floor within the casing leading from the side of the casing opposite the wall opening to the lower edge of such opening, a tubular guide slideable in the casing and having the lower end thereof made up of a plurality of pivotally connected segments whereby the guide may be curved along an arcuate path in moving outwardly through the opening across said floor, a pair of latch members pivotally supported upon each segment, the pairs of latch members of the segments being in a line extending longitudinally of the guide, the latch member of each pair including a bill for engagement with a notch in the adjacent other latch member, said pairs of latch members being oscillated relative to one another to a position in which the bills and notches thereof are out of engagement when the guide segments are disposed in a straight line, means carried by the casing for effecting the oscillation of the pairs of latch members relatively for the interconnection of the bills and notches thereof as the segments move from the casing into a curved path whereby said latches secure the segments together against relative movement, a flexible tubular bit stem extending through the guide, an apertured drill bit upon the lower end of the bit stem, and a drill stem connected to the other end of the bit stem.

10. A lateral drilling mechanism for wells, comprising an elongated tubular casing adapted to be disposed vertically in the lower end of a well hole and having a side wall opening, a downwardly extending curved floor within the casing leading from the side of the casing opposite the wall opening to the lower edge of such opening, a tubular guide slideable in the casing and having the lower end thereof made up of a plurality of pivotally connected segments whereby the guide may be curved along an arcuate path in moving outwardly through the opening across said floor, a pair of latch members pivotally supported upon each segment, the pairs of latch members of the segments being in a line extending longitudinally of the guide, the latch member of each pair including a bill for engagement with a notch in the adjacent other latch member, said pairs of latch members being oscillated relative to one another to a position in which the bills and notches thereof are out of engagement when the guide segments are disposed in a straight line, means carried by the casing for effecting the oscillation of the pairs of latch members relatively for the interconnection of the bills and notches thereof as the segments move from the casing into a curved path whereby said latches secure the segments together against relative movement, a flexible tubular bit stem extending through the guide, an apertured drill bit upon the lower end of the bit stem, a drill stem connected to the other end of the bit stem, the said flexible and metal linings in the bit stem being flanged at their ends and the bit and drill stem functioning to compress the flanged ends of the linings to maintain the latter in position in the bit stem.

11. A lateral drilling mechanism of the character stated, comprising a tubular casing designed to be vertically disposed in a well hole, the casing having a side wall opening, a tubular

guide slidable through said casing, means in the casing for directing the guide laterally through said opening, said guide comprising a plurality of hingedly connected segments constructed and arranged whereby the guide may be turned laterally through an arcuate path, latching elements carried by the segments of the guide upon those sides thereof which are located upon the concave side of the arc of the path followed by the guide, means carried by the casing adjacent to said opening for actuating said latching elements to couple together the elements of adjacent segments as the guide is moved outwardly from the casing and to uncouple the latching elements of the adjacent segment as the guide is moved back into the casing, a flexible bit stem extending through the guide to the lower end thereof, and a bit carried upon said stem upon the outside of the said lower end of the guide.

12. A drilling mechanism as set forth in claim 11 in which said bit stem is of tubular form for conducting drilling fluid to the bit, the bit stem being operatively coupled to a drill pipe, and a single pipe body forming the upper part of said tubular guide and slidably extending into the tubular casing, said pipe through a portion of its length, from the upper end thereof, being of a diameter to receive the coupling of the drill stem.

13. A lateral drilling mechanism for wells, comprising a tubular casing designed to be disposed vertically in the well hole, and having a side wall opening, a tubular guide extending through said casing to said opening and comprising a plurality of hingedly connected segments, means in the lower part of said opening for guiding said tubular guide laterally through the opening along an arcuate path as the guide is lowered, a pair of latching elements pivotally supported upon each segment upon that side of the segment which is upon the inner side of the arc formed by the guide when the same is extended from the casing, a pair of latch actuating rollers supported upon the inner side of the casing immediately above said opening and between which the latches of the segments pass upon longitudinal movement of the guide, said latches being constructed and arranged so that upon passage between the rollers upon outward movement of the guide from the casing each of pair of latches will be coupled together and each will be operatively coupled with a latch of an adjacent segment whereby the guide segment will be permanently secured in an arc, a flexible drill stem extending through said guide and adapted to have rotary and axial movement therein to be extended from the lower end of the guide, a bit carried upon the lower end of the drill stem, and means for coupling a well pipe with the other end of the drill stem.

14. A lateral drilling mechanism as set forth in claim 13 in which said flexible bit stem is of tubular and articulated form and said bit is of hollow construction having fluid outlet apertures in communication with the interior of the tubular bit stem.

15. A lateral drilling mechanism as set forth in claim 13 in which the pivotal connecting means between the segments of the tubular guide comprises a rib member extending axially of each segment from the side opposite from the latching elements, the ends of the adjacent rib members of the segment being pivotally coupled together for relative oscillation of the segments on axes extending transversely of the tubular guide, said ribs coacting to form a continuous supporting runner for the tubular guide in its movement into and out of the tubular casing.

16. A lateral drilling mechanism for wells, comprising a tubular casing adapted to be disposed vertically in the well and having a side wall opening, an arcuate floor in the lower part of the tubular casing extending upwardly and across the same from the lower edge of the opening, a tubular guide extending through the casing from the top thereof to said opening and comprising in the lower end portion thereof a plurality of segments, said arcuate floor functioning to guide the tubular guide laterally along an arcuate path in the downward movement of the guide through the casing, a rib member formed from the outer side of each segment and extending axially thereof and disposed upon the outer side of the arc formed by the guide in extending from the casing, pivotal connecting means between said ribs whereby the same cooperate to form a continuous runner adapted to slide over said floor, latching elements carried by said segments upon the sides thereof directly opposite from the ribs, means for effecting the coupling of said latching elements together upon outward movement of the guide to rigidly maintain the segments joined to form an arc, said last means also effecting the disconnecting of the latching elements upon movement of the tubular guide inwardly, a roller carrier for the tubular guide upon and adapted to have limited movement on said floor in the direction of movement of the guide thereover, means for effecting the automatic coupling and uncoupling of the free end of the guide and the roller support as said free end moves inwardly and outwardly over the floor, a flexible bit stem extending through said guide and adapted to have rotary and axial movement therein, a bit connected with the lower end of said stem, and means for coupling the other end of the stem with a well pipe which extends into the upper end of the guide.
